CLAIM

The ornamental design for a mason jar lid, as shown and described.

DESCRIPTION

FIG. 1 is a bottom rear perspective view of a mason jar lid showing our new design;

FIG. 2 is a bottom front perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The dashed broken lines and unshaded areas within them in the figures illustrate portions of the mason jar lid that form no part of the claimed design.
